(57) **CLAIM**

(51) LOC (12) Cl. **24-02**

The ornamental design for an electronic stethoscope, as shown and described.

(52) U.S. Cl.

DESCRIPTION

USPC **D24/134**

FIG. 1 is a perspective view of an electronic stethoscope showing our new design;

(58) **Field of Classification Search**

FIG. 2 is a front view thereof;

USPC D24/134, 133; 181/131, 132, 137; 381/95, 96; 600/528

FIG. 3 is a rear view thereof;

CPC .. H04R 1/46; A61B 7/04; A61B 7/003; A61B 5/024; A61B 5/7282; A61B 5/742

FIG. 4 is a top view thereof;

See application file for complete search history.

FIG. 5 is a bottom view thereof;

(56) **References Cited**

FIG. 6 is a right side view thereof;

U.S. PATENT DOCUMENTS

FIG. 7 is a left side view thereof;

D445,184 S * 7/2001 Meyer D24/134
D477,405 S * 7/2003 Sommerfeld D24/134
D527,819 S * 9/2006 Poulsen D24/134
D635,667 S * 4/2011 Soerensen D24/134

FIG. 8 is an enlarged front view of 8-8 portion of FIG. 2; and,

FIG. 9 is an enlarged perspective view to illustrate another state thereof.

The broken line showing of the electronic stethoscope is included for the purpose of illustrating portions of the electronic stethoscope and forms no part of the claimed design.
